UNITED STATES PATENT OFFICE.

STALEY D. POOLE, OF MOLINE, ILLINOIS, ASSIGNOR TO DEERE & COMPANY, OF MOLINE, ILLINOIS, A CORPORATION OF ILLINOIS.

PLOW.

1,112,148.

Specification of Letters Patent. Patented Sept. 29, 1914.

Application filed October 30, 1906. Serial No. 341,267.

To all whom it may concern:

Be it known that I, STALEY D. POOLE, citizen of the United States, residing at Moline, in the county of Rock Island and State of Illinois, have invented certain new and useful Improvements in Plows, of which the following is a specification, reference being had therein to the accompanying drawing.

10 This invention relates to improvements in riding plows.

The objects of the invention and the manner in which the parts are constructed and related in such way as to reach the ends 15 aimed at, will be readily understood from the description given below in connection with the drawings.

Figure 1 is a plan view of a plow embodying my improvements; Fig. 1^a is a detail view of the forward furrow corner of the wheel frame; Fig. 2 is a side elevation as seen when looking at the plow from the furrow side; Fig. 3 is a side elevation as seen when looking at it from the land side; Fig. 25 4 is a side elevation of the parts adjacent to the land wheel, the latter being removed; Fig. 5 is a similar view with the parts in different relative positions; Fig. 6 is a plan view of the parts shown in Figs. 4 and 5; Fig. 7 is a section on the line 7—7 of Fig. 6; Fig. 8 is a sectional view taken on the line 8—8 of Fig. 6.

The construction shown in the drawings has two principal frames, one of which I shall term the wheel frame and the other the plow frame. Although some of the parts may be found in earlier plows, I will briefly note them here, that the novel features may be fully understood. The wheel frame is formed of two bent parts 1 and 2, the bar 1 being shaped to have the longitudinally extending part 3 with the cross bar 4 at the front, extended laterally as at 5, and the backward turned bar 6 at the rear. The other bar 2, of this wheel frame or main frame, is shaped to have the inclined rear part 7 and the longitudinally arranged part 8, the rear end of this also being bent backward for a short distance. At the front end 50 it is turned laterally at 9 and rigidly secured to the front part 4 of the other bar. This frame is supported upon the three wheels 10, 11 and 12, that at 10 being a front staggered, or inclined, furrow wheel, that at 11 being a rear furrow wheel also staggered or

inclined, and that at 12 being the land wheel and substantially vertical.

The rear furrow wheel 11 is carried by a spindle 14 the upright part of which is swiveled in any suitable manner in a bearing carried by the main wheel frame. The upper end of this spindle has a crank arm 15 connected with a forwardly extending steering rod 16. The front furrow wheel 10 is carried by a spindle 21 which is swiveled in a suitable bearing 20 carried by a bar 19 secured to the main frame bars 5 and 8, as shown in Fig. 1^a, and suitable devices arranged to be operated by a hand lever 23 are provided for adjusting the spindle 21 up and down in relation to the frame. These devices in themselves do not constitute a part of the invention covered by the present application and need not be described in detail. To the upper end of the spindle 21 is 75 adjustably secured a casting having a forward extending arm 35 to which a steering pole or tongue 40 is secured and a rearward extending arm 36 with which the front end of the steering rod is connected. The land 80 wheel is mounted in a peculiar manner which will presently be described in detail.

In or upon the wheel frame or main frame above described is mounted the plow frame. This comprises longitudinal bars such as are shown at 42, 43, 44, connected at their front ends by cross brace bars 45 and at their rear ends by the inclined cross bar 46. For increasing the strength and stiffness of the frame supplemental brace bars can be used, as shown at 47. Upon this frame, and mounted transversely thereof are the crank shafts 48 and 49. The forward crank shaft 48 is mounted in boxes at 50 on the frame bars 42, 44, and the rear crank shaft 49 is 95 mounted in similar boxes 50^a, one of these being carried by the rear inclined bar 46. These crank shafts have bearings also on the wheel frame or main frame, the boxes for the front shaft being shown at 53, 54, and those for the rear shaft at 53^a, 54^a. To this frame, now being described, are secured the standards 51 and the plow bodies 52.

The plows and the plow frame which directly supports them, are raised and lowered 105 in horizontal parallelism, the radii of the cranks of the front shafts being substantially equal to the radii of the rear cranks. The two shafts are flexibly connected together in a way to be described so that they 110

will vibrate simultaneously and in substantial unison. The land wheel 12 is supported upon a spindle 55, this wheel having a toothed wheel 66 secured to it at the inner end of its hub 67, which toothed wheel is for a purpose to be set forth below. The spindle 55 is carried by a radius arm 56, which at 57 is connected to the rear crank shaft 49, there being a lateral extension of this shaft at 49^a projecting toward the land side beyond the box 53^a which connects the crank shaft to the wheel frame. 58 is a plate secured to this shaft extension and having a recess at 58^a in which the radius arm 56 is situated. 59 is a ratchet segment at the edge of the plate 58. 60 is a lifting lever pivoted to the plate 58 and having its short arm 61 connected through a link or links 62 to the radius arm 56, and this lever has a spring-actuated detent engaging and interlocking with the teeth of the segment at 59. Power can be exerted through the lever 60 in such way as to cause the radius arm 56 to move forward or backward in relation to the plate 58 and thereby raise or lower the framework upon the land wheel as is indicated by the relative positions of the wheel-frame and shaft 55 in Figs. 4 and 5.

The plow frame and plows can be raised or lowered in relation to the main frame or wheel frame by either of two sets of devices, respectively constructed and operated as follows. 68 is a hand lever connected to the rear crank axle by means of a bracket casting 69. If the lever be pushed forward it rocks the crank shaft 49, 49^a in the bearings 53^a, 54^a and throws the cranks and the intermediate part of the shaft upward thus lifting the rear end of the plow frame and the plows. Such rocking forward of the crank shaft 49, 49^a, throws backward the plate 58. This plate is connected by the link 70 to the crank 71 on the end of the forward crank shaft 48 and consequently when the plate 58 swings back it causes the cranks of the crank shaft and the central part thereof to rise, which results in lifting the front end of the plow frame, and as the two crank shafts are, by the devices just referred to each operated in unison, both ends of the plow frame rise and fall simultaneously.

At the time the plows and plow frame reach the uppermost point of their travel, the detent at 72 on the lever 68 enters a recess in the lock segment 74 and engages with a shoulder at 73 which prevents the lever from moving in the opposite direction and holds the crank shafts against downward movement. The detent 72 is connected with a thumb latch 75 by which it can be released at will.

When the plows are down in their lowermost position in relation to the main frame, they, and the plow frame, are locked by the catch at 76. This consists of a pin or bolt

77 with which engages a coiled spring 78, these parts being carried by a bracket 79 cast with the bracket 69. This lock is released by a foot trip having the trip arm or crank arm 80 carried by the shaft 81 supported at its inner end in the metal of the brackets 69, 79, and at its outer end supported in a bearing at 82 formed on the aforesaid plate 58. The shaft 81 has a crank arm 83 shaped to provide a pedal 84 by which the operator can, with his foot, rock the shaft in such way as to release the lock pin 77.

The other set of devices (supplemental to the hand lever 68 and its connections) for causing the rocking of the crank shafts and the lifting of the plows and plow frames, comprises the following. 85 is a sliding bolt mounted on the radius arm 56. It moves in a way provided by the guides 86, 87. It is so arranged that it can be pushed into the path of rotation of the toothed wheel 66, mentioned above, rigid with the hub of the land wheel. To push this bolt 85 toward the toothed wheel it is connected with the crank 83 of the shaft 81 by means of the link 88. When the shaft 81 is rocked by force applied to the pedal 84, the link 88 transmits motion to the bolt 85 and thrusts its lower end into the path of the toothed wheel 66. The instant the wheel engages with this bolt its rotation is stopped and the draft of the team now transmitted to the wheel compels it to force the radius arm 56 backward and as this plate is, through the lever 60 and the detent and segment 59 rigidly locked with the plate 58, the latter is also thrust backward and the crank shaft 49, 49^a is rocked in such manner as to cause the plow frame and the plows to be lifted. And the link 70 being pivoted to the plate 58, the lifting force is transmitted also to the front crank shaft which lifts the front end of the plow frame. The pressing down of the bolt 85 by the treadle 84 follows quickly after the loosening of the lock 77.

90 is a coiled spring combined with the bolt 85 and tending to thrust it upward to insure quick disengagement. This disengagement will occur instantly after the operator removes his foot from the pedal which he does as soon as the lever 68 has reached the position where it is locked against the shoulder 73 on the segment bar 74.

The devices which lift the plows are assisted by one or more springs. One is shown at 97 having its rear end connected at 98 to the frame, and its front end connected to an extension 99 of the hand lever 68. Preferably the spring or springs and attachments are so arranged that they will exert a reduced force when the plows are in their working position, but with an increasing force after the plows have been started upward by the lifting devices. 97 indicates

brother of the lifting springs, it having a suitable connection at the rear with the frame, and at the front being connected with the lever 59 of the crank shaft 48.

Although I have above described somewhat in detail the particular form of construction which is illustrated in the drawings, I wish it to be understood that I do not limit myself to that particular form or any other, so far as concerns many of the details. It will be seen that the essential features can be embodied in a mechanism much simpler in construction. Any one of the three plow bodies can be mounted upon a structure in such way as to carry out the invention. In such a case also the plow can be supplied with means for raising it and lowering it to its working position, of such sort that the draft from the draft carriers can at will be caused to lift it from one of its positions to the other.

When considering the mechanism which I have provided for adjusting the plow or draw vertically, it will be seen that one set of devices, swinging plate 58, bails 48, etc., etc., can be used to vary their positions vertically in relation to both the land wheel and the front furrow wheel, and the other set of devices, radius arm 56, lever 60, etc., can be used to vary their vertical position in relation to one of these wheels only. Thus when it is desired to remove the plows from the ground entirely, they can be lifted in relation to both the land and the front furrow wheel; but when the plows are at work and it is desired to vary the depth of the furrows, it can be done by the devices which affect the relative vertical positions of the land wheel only. These two sets of lifting devices are shown as intimately connected together, the wheel carrier 56 being arranged in close relation to the plate 58, and the lever 60 and its connections being interposed between them. But other forms of construction and relative arrangements can be used.

While I have shown means for stopping the rotation of the land wheel in relation to its carrier, as part of the mechanism whereby the draft from the draft devices can be utilized for the lifting of the plows, there can be variation in this respect. When devices possessing the capabilities of those shown are employed, it will be seen, that in that I provide what may be regarded as a fulcrum on the ground which causes the relative movement of some of the parts on the machine in relation to others, which movement results in the lifting of the plows; for the stoppage of the rotation of the land wheel provides, for the moment, a body which temporarily engages with the ground and causes the backward swinging of the crank arm parts below the shaft 49, thus effecting the lifting of the plow.

In lands of some sorts, as for instance

where stones or other obstructions are frequent, it is desirable to have the plow or plows capable of automatically rising and falling instantly and without the application of power. In the present machine, when plowing lands of that sort, the dog 77 is turned out of engagement with the segment and is locked out by means of a cotter key, or in any other suitable way. After that is done the plow or plows hang freely, the spring or springs in connection with the suction of the soil being depended upon to sustain them in their normal position.

What I claim is:

1. In a mechanism of the class described, the combination of a frame, a plow, a wheel on the land side of the plow, a support for said wheel movably carried by the frame, a wheel on the furrow side of the plow, plow lifting devices mounted on the frame, means for adjustably connecting the land wheel support to the said lifting devices whereby the latter are actuated by movement of the support, and means operable at will by the force of the draft for moving the said support, substantially as set forth.

2. In a mechanism of the class described, the combination of a wheel frame, wheels supporting said frame comprising a furrow wheel and a land wheel, a plow, a crank shaft journaled on the wheel frame and operatively connected to the plow, a radius arm mounted to swing about the axis of the crank shaft and having at its outer end an axle on which the land wheel is mounted, adjustable means for connecting the radius arm to the crank shaft in different angular positions in relation thereto, and means for locking the land wheel against rotation relative to the radius arm, substantially as set forth.

3. In a mechanism of the class described, the combination of a wheel frame, ground wheels supporting said frame, a plow, a swinging radius arm on which one of said wheels is mounted, means for lifting the plow relative to the wheel frame, adjustable connections between the radius arm and lifting means, and means operable at will by the draft for swinging the radius arm to actuate the lifting means, substantially as set forth.

4. In a mechanism of the class described, the combination of a frame, a plow, a wheel on the land side of the plow, a carrier for said wheel movably mounted on the frame, a wheel on the furrow side of the plow, plow lifting devices mounted on the frame, and means for adjustably connecting the land wheel carrier to the said lifting devices whereby the latter are actuated by movement of the carrier, said carrier being movable at will by the turning force of the land wheel to elevate the plow, substantially as set forth.

5. In a mechanism of the class described, the combination of the plow, the furrow wheel, the land wheel, the crank shaft supported on the wheels and operatively connected with the plow, the movable carrier on which the land wheel is rotatably mounted, said carrier being mounted to swing about the axis of the crank shaft and relative to said shaft, means for stopping the 10 rotation of the land wheel relative to the carrier, and means for locking the wheel carrier to the crank shaft, substantially as set forth.

6. The combination of a plow, a wheel frame, wheels supporting the frame comprising front and rear furrow wheels and a land wheel, a front crank shaft, a rear crank shaft, each of said shafts being journaled on the wheel frame and operatively connected to the plow, a radius arm adjustably connected to one of the crank shafts and carrying a spindle on which the land wheel is mounted, and means for locking the land wheel against rotation relative to the 20 radius arm, substantially as set forth.

7. In a mechanism of the class described, the combination of a wheel frame, ground wheels upon which said frame is supported, a plow, mechanism for lifting the plow 30 relative to the frame connected to the plow and frame, means operable at will for applying the force of the draft to the lifting mechanism to raise the plow, means for adjusting the plow to work at different depths, and automatic means other than said adjusting means for locking the plow down at any adjusted depth, substantially as set forth.

8. In a mechanism of the class described, 40 the combination of a wheel frame, ground wheels supporting said frame, a plow, a swinging radius arm on which one of said wheels is mounted, means for lifting the plow relative to the wheel frame, adjustable connections between the radius arm and lifting means whereby the plow can be adjusted to work at different depths, means operable at will by the draft for swinging the radius arm to actuate the lifting means, 50 and means for automatically locking the plow down at any adjusted depth, substantially as set forth.

9. In a plowing mechanism, the combination of the front furrow wheel, the rear furrow wheel, both arranged to swing transversely relatively to the draft lines, the land wheel, the frame supported on the said three 55 wheels and normally held bodily fixed relatively to the ground, a series of plow bodies rigidly secured together by framework, a front vertically moving support for the plow frame mounted on the main frame, a second vertically movable support connected to the rear part of the plow frame, power transmitting mechanism mounted on the frame 60

and connected to the said rear support and to the land wheel for lifting the plows through the land wheel and the main frame under the force exerted on said parts when the plow mechanism is forwardly propelled. 70

10. In a plowing mechanism, the combination of the front furrow wheel, the rear furrow wheel, both arranged to swing transversely relatively to the draft lines while at work, the land wheel, the frame supported on the said three wheels and normally held bodily fixed relatively to the ground, plows supported upon and vertically movable relatively to the frame, power transmitting mechanism mounted on the frame and connected to the land wheel and to the plows, for moving them upward, and an optionally controlled lock for holding or releasing the said transmitting mechanism. 75

11. In a plowing mechanism, the combination of the front furrow wheel, the rear furrow wheel, both said wheels arranged to swing while at work transversely relatively to the draft lines, the land wheel, the frame supported on the said three wheels, the vertically swinging carrier for the land wheel mounted on the frame, said wheel having its axis situated in advance of the axis of the carrier, plows supported upon and movable vertically in the frame, power transmitting mechanism mounted on the frame and adapted to lift the plows when the frame rises, said transmitting mechanism being connected to the land wheel, and optionally controlled means for preventing the land wheel from moving backward. 90

12. In a plowing mechanism, the combination of the diagonally arranged series of plow bodies rigidly secured together by framework and adapted to have draft devices connected thereto, the main frame, the suspending and lifting devices connected to the rear part of the plow frame, the front furrow wheel, the rear furrow wheel, both of said wheels being adapted to swing transversely of the lines of draft, the land wheel, the swinging carrier mounted on an axis on the frame and normally extending from said axis forward to the wheel axis and adapted to swing backward under the force of the draft, power devices between said carrier and the rear support for the plow frame, means for optionally permitting or preventing the rotation of the wheel on its axis, and means for leveling all the plow bodies of the series relatively to the land wheel and the front furrow wheel. 110

13. In a plowing mechanism, the combination of the inclined series of plow bodies rigidly connected together by framework, the main frame, the swinging bail mounted on the main frame and connected to the rear part of the plow frame for suspending and lifting it, the swinging bail for the front end of the draft frame, draft devices at 120 125 130

- tached to the plow frame, the front furrow wheel, the rear furrow wheel, both of said wheels being adapted to swing transversely relatively to the draft line, the land wheel, 5 the swinging wheel carrier normally extending forward from the axis of its mounting on the main frame to the wheel axis, and adapted to swing backward with the wheel to lift the frame, means connecting said land 10 wheel to said bail and transmitting lifting power from the draft devices to the plow frame through the wheel and the carrier, and means for controlling the movements, bodily, of the land wheel.
- 15 14. In a plowing mechanism, the combination of the front furrow wheel, the rear furrow wheel, the land wheel, the frame supported on said wheels and normally held
- bodily in fixed relation to the ground, but adapted to be automatically lifted at its 20 land side, a series of plows movably connected to the frame, a rocking shaft element on the frame, a radius arm loosely connected to the rocking shaft element and carrying the land wheel, and means for causing the 25 land wheel to swing the radius arm backward whereby it lifts the land side of the frame and simultaneously lifts the plows in the frame.
- In testimony whereof I affix my signature, in presence of two witnesses

STALEY D. POOLE.
